(57) **CLAIM**

The ornamental design for a shower caddy with expandable shelves, as shown and described.

DESCRIPTION

FIG. 1 is a perspective view of a shower caddy with expandable shelves in accordance with my design;

FIG. 2 is a top plan view of the shower caddy with expandable shelves shown in FIG. 1;

FIG. 3 is a front elevational view thereof;

FIG. 4 is a right side elevational view thereof;

FIG. 5 is a left side elevational thereof;

FIG. 6 is a rear elevational view thereof;

FIG. 7 is a bottom plan view thereof; and,

FIG. 8 is a perspective view similar to FIG. 1, but showing the shelves in an expanded condition.
